UNITED STATES PATENT OFFICE.

EWELL W. PENDERGRAFT, OF VICKSBURG, MISSISSIPPI.

SASH ATTACHMENT.

1,378,718.

Specification of Letters Patent. Patented May 17, 1921.

Application filed May 10, 1919. Serial No. 296,109.

To all whom it may concern:

Be it known that I, EWELL W. PENDERGRAFT, a citizen of the United States, residing at Vicksburg, in the county of Warren 5 and State of Mississippi, have invented new and useful Improvements in Sash Attachments, of which the following is a specification.

This invention relates to sashes, the object being to provide an attachment for balancing window sashes without the use of the usual sash weight.

Another object of the invention is to provide a sash attachment by means of which a 15 sash, that is, the upper and lower window sash, will act to balance one another, to eliminate the use of weights and to provide for a simultaneous movement of both sashes, so that when the lower sash is raised, the upper 20 sash will be lowered to provide proper ventilation.

With the above and other objects in view, the invention includes the following novel features and details of construction, to be 25 hereinafter more fully described and illustrated in the accompanying drawings.

In the drawings:

Figure 1 is a fragmentary sectional view illustrating the application of the invention. 30 Fig. 2 is a detail elevation of the attachment looking at the reverse side from that shown in Fig. 1.

Fig. 3 is a sectional view on the line 3—3 of Fig. 1.

Fig. 4 is a similar view on the line 4—4 of Fig. 1.

Fig. 5 is a sectional view on the line 5—5 of Fig. 1.

Fig. 6 is a sectional view on the line 6—6 of Fig. 2.

Fig. 7 is a bottom edge view of the attachment.

Referring to the drawings in detail, like characters of reference denote corresponding views throughout the several views.

In illustrating the use of the invention, there is shown at 10, a portion of a window casing, the upper sash being indicated at 11 and the lower sash at 12.

50 The invention comprises a plate 13, which is preferably rectangular in shape and is provided with openings 14 for the passage of screws or analogous fastening devices,

for the purpose of securing the plate to the window casing. Riveted, or otherwise secured to the plate 13, is a substantially **U** shaped bracket 15, which is spaced from the plate 13 to provide a housing or grooved pulley 16, the latter being mounted upon a pintle or stud 17, which is secured to and 60 connects the bracket 15 and the plate 13.

Operating over the pulley 16, is a chain or cable 18, the latter passing through openings 19, which are surrounded by inclined guides 20. These openings and guides are 65 formed by slitting the plate 13 at a point indicated at 21 and pressing the material of which the plate is formed inward, as shown in Fig. 4, so that the chain 18 will pass along the guides 20 and through the openings 19 and have one of its ends connected to the upper sash 11, and its other end to the lower sash 12. It is, of course, obvious that 70 one of these devices will be positioned upon opposite sides of the sash frame or casing, 75 and that one sash will act as a counter-balance weight for the other sash, so that the said sashes will remain in any desired raised or lowered position. By connecting the sashes in the manner described, a movement 80 of one sash will cause a simultaneous movement of the other sash, so that should the lower sash be raised, the upper sash will be correspondingly lowered and thereby insure proper ventilation.

The invention is susceptible of various changes in its form, proportions and minor details of construction and the right is herein reserved to make such changes as properly fall within the scope of the appended 90 claim.

Having described the invention, what is claimed is:

A sash attachment comprising a plate 95 formed with spaced aligned slits and pressed to provide elongated openings and inclined guides positioned over said openings, a substantially **U**-shaped bracket secured to the plate between the openings, a grooved pulley rotatably mounted between the bracket 100 and plate above the opening, and a flexible element passing over said pulley, dropping through the respective openings and directed to the sash by said guides aforesaid.

In testimony whereof I affix my signature. 105
EWELL W. PENDERGRAFT.
